No. 681,659.

Patented Aug. 27, 1901.

J. SALLADE.

ENVELOP.

(Application filed May 14, 1901.)

(No Model.)

UNITED STATES PATENT OFFICE.

JACOB SALLADE, OF MILTON, PENNSYLVANIA, ASSIGNOR OF ONE-HALF
TO BENJAMIN F. JOHNSON, OF RICHMOND, VIRGINIA.

ENVELOP.

SPECIFICATION forming part of Letters Patent No. 681,659, dated August 27, 1901.

Application filed May 14, 1901. Serial No. 60,143. (No model.)

To all whom it may concern:

Be it known that I, JACOB SALLADE, a citizen of the United States, residing at Milton, in the county of Northumberland and State 5 of Pennsylvania, have invented certain new and useful Improvements in Envelops, of which the following is a specification.

The envelop which is the subject of this patent is designed to contain offerings for the 10 support of the church and separate offerings for kindred purposes, the purpose of the separate offerings being designated on separable parts of the envelop, each offering being sealed in its separable part, so that each offering 15 may be applied as intended, and the precise improvement will be pointed out in the claim hereto appended in connection with the accompanying drawings, in which—

Figure 1 shows a blank paper with its lines 20 of gum and of separation by which a twin envelop is formed, each separable part having printed thereon the purpose of the separate offerings. Fig. 2 shows the envelop with the side folds or overlaps sealed. Fig. 3 shows 25 the twin envelop with its side and end flies or folds sealed to close the separable twin parts. Fig. 4 shows in section the closed separable twin parts, each part containing an offering. Fig. 5 shows the envelop with a surface separable 30 line and the printing thereon indicating the purpose of the offerings.

The blank is produced with two side and two end flies or fold parts similar to an ordinary envelop, each end fold 1 having its edge 35 gummed, one of the side folds 2 having its edge gummed. Crossing meditately the side folds is a gummed line 3, whereby when the side folds are closed and sealed the envelop is formed into twin parts 4 and 5, each part 40 being closed at the gummed line 3 and provided with an end fold, so that each twin part will form a complete envelop. An external transverse line indicates the middle of the width of the transverse gummed line 3 as the 45 point at which the twin parts may be separated, with each part intact as a closure for what it contains after the end folds are sealed.

The transverse gummed line 3 preferably extends across each side fold and is wide enough to allow each end part to be closed when the 50 parts are separated, as shown by dotted lines G G in Fig. 2. This separable mark may be a weakened surface line 7, as in Fig. 5, at which the parts may be separated; but I prefer that the mark be a line of perforations 8, 55 whereby the envelop parts may be separated by tearing. Each part may bear any suitable printed matter, each having the same or a different number. In the example shown the separate envelop parts bear the same number "134," one part having the following 60 printed matter: "Weekly offering, First Baptist Church, Milton, Pa., January 15, 1901," and the other part having the months of the year, and for certain months the words "Education," "Publication society," "Foreign 65 missions," "Home missions," "Loan fund," and "State missions" are printed, indicating for what the offering is made. The twin parts of the envelop with their contents having 70 been separated, each part with its contents then becomes an offering for a specific purpose. The side folds being fastened together at their lapped longitudinal edges at the same time will cause the side folds to be 75 fastened on their inner sides to the inner side of the body of the envelop along the internal transverse gummed line, thus forming a double-ended pocket, each having an end - closing fold and separable along the 80 transverse gummed line to keep distinct and separate the contents sealed in each part.

I have stated that the folds are provided with gum; but my improvement comprehends any means of fastening the folds into twin 85 parts and an indicating separable line therefor.

I claim—

As a new article of manufacture, a twin envelop folded to provide side laps to form a 90 longitudinal central overlapping gummed seam terminating at the open opposite ends and on the same side of the twin envelop, the inner walls of the side laps gummed in trans-

verse lines mediate of their length, and in
folded position, crossing the longitudinally-
lapped seam, and a weakened line crossing
said lapping gummed seam mediate of the
5 width of the gummed transverse lines, and
gummed end flaps to seal the open ends of
the gummed-seamed side laps.

In testimony whereof I affix my signature
in presence of two witnesses.

JACOB SALLADE.
